DESIGN FOR A MINIATURE BUREAU OR SIMILAR ARTICLE

Nathaniel Hyman, New York, N. Y.

Application September 25, 1944, Serial No. 115,438

Term of patent 3½ years

(Cl. D34—15)

To all whom it may concern:

Be it known that I, Nathaniel Hyman, a citizen of the United States of America, residing in New York city, county of New York, and State of New York, have invented a new, original, and ornamental Design for a Miniature Bureau or Similar Article, of which the following is a specification, reference being had to the accompanying drawing, forming part thereof, wherein,

ature bureau or similar article, showing my new design, and

Figure 2 is a side elevational view thereof.

The back of the design is plain and unornamented.

I claim:

The ornamental design for a miniature bureau or similar article, substantially as shown and described.

NATHANIEL HYMAN.
